UNITED STATES PATENT OFFICE.

HARRIS M. BENEDECT, OF CINCINNATI, OHIO.

SHELF-MARKER.

1,230,653.

Specification of Letters Patent. Patented June 19, 1917.

Application filed February 8, 1917. Serial No. 147,458.

To all whom it may concern:

Be it known that I, HARRIS MILLER BENEDECT, a citizen of the United States, residing at Cincinnati, in the county of Hamilton and State of Ohio, have invented a new and useful Shelf-Marker, of which the following is a specification.

This invention relates to a shelf marker, one of its objects being to provide a device which can be applied readily to the front portion of a rack or case so as to hang in front of a space from which has been removed a book, said marker displaying data indicating the title, etc., of the book removed so that it thus becomes possible to readily locate the proper space in which to reinsert the removed book.

A further object is to provide a marker which, when not in use as such, will rest upon the book to which it belongs and will serve as a false partition to separate said book from the next adjoining one and to hold the book in an upright position when the next adjoining one is removed.

Another object is to provide a simple form of device which will hold a tag on which suitable designating matter may be displayed.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings:

Figure 1 is a front elevation of a portion of a rack or case showing the present improvements combined therewith.

Fig. 2 is a perspective view of one of the markers.

Fig. 3 is a perspective view of a modified form of marker.

Fig. 4 is a perspective view of another modification.

Referring to the figures by characters of reference 1 designates a rod adapted to be extended along the lower edge of the front portion of a shelf, and on this rod are mount-

ed the markers used in connection with the books on the shelf thereunder. As shown particularly in Fig. 3, each marker is formed of a plate 2 one end of which is bent back upon itself to form a split sleeve 3 for loosely engaging the rod 1. The other end of the plate is bent back upon itself to form a clip 4 which extends partly or entirely across the back of an opening 5 in the lower portion of the plate. A wing 6 is extended forwardly from one side edge of the plate and is preferably disposed at right angles to said plate, this wing being substantially triangular and having one end portion extended beyond the end of the plate as shown at 7.

A clip such as described is adapted to be used in connection with each book and when all of the books are on a shelf, the clips provided therefor will rest upon the respective books with the wings 6 projecting downwardly between the books as shown at the right of Fig. 1. When a book is removed, the clip resting thereon will swing downwardly to a substantially vertical position as shown at a in Fig. 1 and by placing a card back of the opening 5 where it will be held by the clip 4, said card having data thereon identifying the removed book, the space in which the book is to be reinserted can be easily located. When the book is inserted in its proper place it will push against the plate 2 and cause it to swing backwardly and upwardly until it rests on the book with the wing 6 interposed between said book and the next adjoining one. Obviously should a book be removed from the shelf, the next adjoining books will be supported, by the markers resting thereon and by the wings lapping said books.

Instead of providing a rod for supporting markers adapted to swing thereon, a flat supporting strip 8 may be employed, this strip being engaged by a clip 9 to which the plate 10 is hingedly attached as at 11.

Instead of slidably mounting the marker on a supporting rod or strip, it can be mounted directly on the shelf. Where this is to be done the device should be made as shown in Fig. 4, there being a clip 12 for tightly embracing the front edge of the shelf and the plate 13 being hingedly connected to this clip as shown at 14. In other respects the device is the same as shown in Fig. 3.

While the device has been described as particularly designed for use in connection

with shelves of books, it can obviously be used in connection with other articles placed on shelves.

What is claimed is:—

- 5 1. A shelf marker including a member mounted for swinging movement and adapted to rest upon an article placed thereunder, and a spacing wing extending from one side of said member.
- 10 2. A shelf marker including a member mounted for swinging movement, and adapted to be held out of normal position by an article thereunder, and a spacing wing extending from one side of the member and adapted to lap one side of the supporting article.
- 15 3. A shelf marker including a member mounted for swinging movement, and adapted to be held out of normal position by an article supported thereunder, means carried by said member for holding a card or the like, and a spacing wing extending from one side of the member.
- 20 4. A shelf marker including a member mounted for swinging movement, and adapted to be held out of normal position by an article supported thereunder, means carried by said member for holding a card or the like, and a spacing wing extending from one side of the member, said wing projecting beyond the free end of the member.
- 25 5. A shelf marker including a support engaging element, a member mounted to swing relative to said element, a clip carried by said member, and a spacing wing extending from one side of the member.
- 30 6. The combination with a support engag-

ing element, of a member mounted to swing therefrom and adapted to be held out of normal position by an article placed thereunder, said member having an aperture therein, a card holding clip extending from the member and adjacent the aperture, and a spacing wing extending from one side of the member.

40

45

7. The combination with a support engaging clip having an aperture for exposing a portion of the engaged support, of a member hingedly connected to the clip and normally hung therefrom, said member being adapted to be engaged and elevated by an article placed in position under the support engaging clip, and a card holding clip upon the free end portion of the member, there being an aperture in the member and adjacent said clip to expose the held card when the member is in its normal position, said card being concealed when the member is supported on an object placed thereunder.

50

55

8. A shelf marker including a clip, a member hingedly connected to the clip, said clip constituting means for engaging a support, a clip upon the free end portion of said member, there being an aperture in the member and adjacent the clip thereon, and a wing extending from one side of the member and projecting beyond one end thereof.
